UNITED STATES PATENT OFFICE.

WALTER A. PAPWORTH, OF SYRACUSE, NEW YORK, ASSIGNOR TO E. C. STEARNS & COMPANY, OF SYRACUSE, NEW YORK.

FLOOR-SCRAPER.

1,170,319.

Specification of Letters Patent.

Patented Feb. 1, 1916.

Application filed April 8, 1912. Serial No. 689,298.

To all whom it may concern:

Be it known that I, WALTER A. PAPWORTH, a citizen of the United States, residing at Syracuse, in the county of Onondaga and 5 State of New York, have invented a new and useful Floor-Scraper, of which the following is a specification.

My invention relates to improvements in a class of tools in which a scraper blade is 10 adjustably attached to a handle and has for its objects the provision of a strong and serviceable tool of few parts having a universal ball and socket adjustment between the blade and the handle.

15 A further object is the provision of a universal ball and socket joint capable of being rigidly clamped in any position, composed of fewer parts than has heretofore been considered necessary for a device of 20 this kind, and yet capable of easy assembly.

These objects are attained by the device shown in the accompanying drawings in which:

Figure 1 is a perspective view showing 25 my scraper assembled with portions cut away to show interior parts. Fig. 2 is a perspective view of the nut F. Fig. 3 is a rear view of the scraper with the handle removed showing the method of assembling. 30 Figs. 2 and 3 show the approximate relative shape of the parts to accomplish their functions of assembly, swinging, and clamping.

A pair of jaws A and B having portions 35 of their contiguous surfaces substantially flat are drawn together upon the scraping blade C by a screw D. In the rear jaw A a substantially spherical socket E is formed having an opening of somewhat less diameter than the greatest diameter of the socket.

40 In the socket E is a nut whose shape is, in general, that of a hemisphere but whose sides and top have been cut away just enough to allow it to be slipped into the socket E when it is turned to just the proper position.

45 There is a threaded hole S through the said nut F so located and directed that when a rod is passed through the mouth of the socket and screwed into the hole in the nut, the latter cannot be turned to the position

which permits it to pass through the mouth 50 of the socket, although it has a considerable freedom of motion in any direction.

G is a screw long enough to pass completely through the nut and clamp against the opposite side of the socket and pinned 55 into the handle H with a pin I.

In operation, a scraper blade is clamped between the jaws, the scraper is seized by the handle with one hand and drawn over the floor or other object to be scraped, downward pressure meanwhile being brought to bear by the other hand on top of the jaws A and B. In case either the nature of the wood or the cutting edge of the scraper are such that a greater or less inclination of the 60 blade would improve the cutting, the handle is loosened, moved to any desired angle and rigidly clamped by a slight twist of the handle.

In scraping floors near walls, posts, or 70 other obstructions the handle may be thrown over sidewise at an angle to enable the operator to conveniently manipulate the tool without scraping his knuckles.

Having thus described my invention I 75 claim as new:

A tool comprising a member provided with a socket having an opening communicating therewith through an integral wall and of lesser diameter than the socket interior, a clamping nut of a form to permit of its entering the socket through said opening and to assume a position within the socket to span said opening, said nut having an aperture registering with said opening 80 when the nut is turned into said spanning position, a handle element and a screw shank on the handle element fitted to the nut aperture and adapted to exert a force 85 on the nut to effect a clamping engagement of the nut and socket, to secure the parts in their relatively adjusted positions.

In testimony whereof I affix my signature in the presence of two witnesses.

WALTER A. PAPWORTH.
